UNITED STATES PATENT OFFICE

159,911

COMBINATION PIANO, RADIO, AND PHONOGRAPH

Louis Luberoff, Jenkintown, Pa.

Application October 11, 1948, Serial No. 149,075

Term of patent 14 years

(Cl. D56—4)

To all whom it may concern:

Be it known that I, Louis Luberoff, a citizen of the United States, residing in Jenkintown, Montgomery County, Pennsylvania, have invented a new, original, and ornamental Design for Combination Piano, Radio, and Phonograph, of which the following is a specification, reference being had to the accompanying drawings, forming part thereof, in which—

Figure 1 is a perspective view of the combination piano, radio and phonograph showing my new design;

Fig. 2 is a side elevational view of the same taken from the left side as viewed in Fig. 1; and

Fig. 3 is a fragmentary perspective view of the upper part of the device as it appears with the lids in raised position.

The characteristic features of my design reside in the portions shown by means of full lines in the drawing.

I claim:

The ornamental design for a combination piano, radio, and phonograph, substantially as shown and described.

LOUIS LUBEROFF.
